FLOCK COVERED GLARE SHIELD

Rex C. Jacobs, Detroit, Mich.

Application March 29, 1937, Serial No. 133,607

6 Claims. (Cl. 296—97)

This invention relates to glare shields and has for its object to provide an improved construction and method of construction for the shield itself.

Heretofore, it has been preferred to provide a rigid metallic framework having one side thereof as a shield hinge member and to completely cover this framework with cloth. The operations involved in making the integral framework by using a combination of rod and tubular members, plus the number of operations involved in forming a neatly fitting cloth covering for the framework, and the cost of these materials, is both tedious and expensive to manufacture. It is the principal object of this invention to teach the method of making a suitable glare shield, scarcely distinguishable from a cloth covered glare shield of the type above referred to, by using a fibrous sheet and a metal hinge member covered by blown flock.

With the above and other ends in view, the invention consists in matters hereinafter more particularly set forth with reference to the accompanying drawing, in which

Figure 1 is an elevation of the shield, partly broken away and in section;

Fig. 2 is a section taken on the line 2—2 of Fig. 1;

Fig. 3 is an elevation, partly shown in section, illustrating a binding for the glare shield;

Figs. 4 and 5 are sections taken respectively on the lines 4—4 and 5—5 of Fig. 3, and

Fig. 6 is an elevation illustrating a step in the method of forming the present glare shield.

Like characters of reference are employed throughout to designate corresponding parts.

The numeral 1 designates a sheet formed preferably of fibrous material, embodying a certain amount of resiliency, yet sufficiently stiff to stand up under the conditions of its use. Secured to one edge of the sheet 1 is a hinge member comprising a tubular bearing portion 2 with wings 3 integral therewith, the tubular portion being held closed by welding the parts 4 together. By bending the metal outwardly from the welded parts 4 shoulders 5 are provided between the wings 3.

Ordinarily the wings 3 spread apart so that the sheet 1 may be conveniently placed therebetween, as shown in Fig. 6. When the sheet 1 is placed between the wings 3 so that its edge engages the shoulders 5, the wings are pressed together so as to imbed them in the sheet 1, and prongs 6, are formed integral therewith and are imbedded in the sheet 1.

It will be noted in Fig. 2, wherein the parts are

shown on an enlarged scale, that the angles necessary for the hinge formation are all exteriorly rounded and formed quite smooth, the wings 3, in being imbedded in the sheet 1, have their exterior surfaces in plane with the exterior surfaces of the sheet 1, and the exposed edges of the sheet 1 are rounded as designated at 7. These characteristics are important in a flock covered glare shield, both from the standpoint of difficulty found in placing flock on angles and the difficulty in keeping it on when once placed, and also in order to give the shield and hinge bracket an appearance having the characteristics of a cloth covering.

When the shield and hinge bracket have been assembled as above described, a plug 7 is placed in one end of the bearing portion 2, the entire surfaces of the sheet 1 and hinge member are sprayed with an adhesive, and while the adhesive is slightly moist or "tacky" finely divided flock is blown thereon. When dry this gives a finish closely resembling cloth.

As shown in Figs. 3, 4 and 5, a trim border 8, formed of such material as leather, may be stitched around the three exposed sides of the sheet 1a. Such a trim protects the edges of the sheet as well as providing an ornamental appearance. It eliminates any possibility of the flock covering wearing off the edges and thus exposing the fibrous sheet. It is especially desirable when the fibrous material of the sheet is such as laminated paper fibre, in which case the tendency for the laminations to separate at the edges of the sheet is entirely eliminated. The trim reinforces the sheet to such an extent that an inexpensive type of fibrous material may be used. The ends of the trim border 8 are secured to the sheet 1a by pronged metal clips 9.

Although a specific embodiment of the invention has been illustrated and described it will be understood that various changes may be made within the scope of the appended claims without departing from the spirit of the invention, and such changes are contemplated.

What I claim is:—

1. A glare shield comprising a sheet of fibrous material, a hinge member having a tubular bearing portion and a pair of wings between which an edge of said sheet is inserted, said wings being imbedded in said sheet whereby their outer surfaces are in plane with the outer surfaces of said sheet, a plug in one end of said tubular bearing portion, and a coating of finely divided flock on all exposed surfaces of said sheet, said hinge member and plug.

2. A glare shield comprising a sheet of fibrous material, a hinge member having a tubular bearing portion and a pair of wings between which an edge of said sheet is inserted, said wings being imbedded in said sheet whereby their outer surfaces are in plane with the outer surfaces of said sheet, prongs on said wings and imbedded in said sheet, and a coating of finely divided flock on said sheet and said hinge member.
- 5 5. The method of making a glare shield which consists in cutting a sheet of fibrous material to size, in forming a hinge member with a bearing portion and a pair of spaced wings, inserting the edge of said sheet between said wings and pressing them together to imbed them in the sheet, coating the sheet and hinge member with adhesive, and blowing finely divided flock thereon.
- 10 10. A glare shield comprising a sheet of fibrous material, a hinge member having a tubular bearing portion and a pair of wings between which an edge of said sheet is inserted, said wings being imbedded in said sheet whereby their outer surfaces are in plane with the outer surfaces of said sheet, a coating of finely divided flock on said sheet and said hinge member, and a reinforcing ornamental binding around the exposed edges of said sheet.
- 15 15. The method of making a glare shield which consists in cutting a sheet of fibrous material to size, in forming a hinge member with a bearing portion and a pair of spaced wings, inserting the edge of said sheet between said wings and pressing them together to imbed them in the sheet,
- 20 20. A glare shield comprising a sheet of fibrous material, a hinge member having a tubular bearing portion and a pair of spaced flange members between which a border portion of the sheet is inserted, means closing one end of said tubular bearing portion, and a coating of finely divided flock on all exposed surfaces of said sheet, hinge member and said means.

REX C. JACOBS.
